UNITED STATES PATENT OFFICE.

HAROLD O. HOLTE, DECEASED, LATE OF PITTSBURGH, PENNSYLVANIA; BY HALVOR HOLTE, ADMINISTRATOR, OF CROOKSTON, MINNESOTA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 2, 1926. Serial No. 120,130.

The invention relates to railway traffic controlling apparatus, and particularly to apparatus of the type comprising governing means controlled by alternating currents flowing in the trackway.

Two forms of railway traffic controlling apparatus embodying the invention will be described and the novel features thereof will then be pointed out in claims.

10 In the accompanying drawings, Fig. 1 is a diagrammatic view showing one form of railway traffic controlling apparatus embodying the invention as applied to a signaling system. Fig. 2 is a view illustrating a modified form of railway traffic controlling apparatus embodying the invention as applied to the control of trains.

Similar reference characters refer to similar parts in both views.

20 Referring first to Fig. 1, the reference characters 1 and 1^a designate the track rails of a stretch of railway track over which traffic normally moves in the direction indicated by the arrow. These rails are divided, 25 by means of insulated joints 2, into a plurality of successive track sections A—B, B—C, etc. Each track section is provided with a transformer designated by the reference character T with a suitable distinguishing exponent and comprising a single primary 4, and two secondaries 5 and 6 having a common terminal d. The primary 4 of each transformer T is constantly connected across the rails adjacent the entrance 30 end of the associated section.

Associated with each transformer T is a vibrating rectifier designated by the reference character D with an exponent corresponding to the location and comprising an 40 operating winding 12 and a vibrating reed 11 shown in the drawing in its central position. The winding 12 of each rectifier D is constantly supplied with alternating current from a suitable source of energy such as an alternator M over line wires 3 and 3^a. The reed 11 of each rectifier D therefore operates continuously and each reed may be roughly tuned, as by a slideable weight 11^a, to mechanical resonance at the frequency of 50 the current supplied to winding 12, but this is not essential.

Each track section is also provided with a polarized direct current relay designated

by the reference character K with an appropriate exponent. Each relay K is at 55 times supplied with current of one polarity or the other from the associated transformer T, through the rectifier D associated therewith, as will hereinafter appear.

The rails of each section are supplied with alternating current by a transformer designated by the reference character J with a suitable distinguishing exponent. The primary 7 of each transformer J is constantly supplied with alternating current from line wires 3 and 3^a. Referring particularly to the apparatus located at point B, when relay K^B is energized, current of one relative polarity, which I will term "normal relative polarity" is supplied to the rails of section A—B, over 70 front contact 27 of relay K^B, the circuit passing from one terminal of winding 8 of transformer J^B, through wire 26, front contact 27 of relay K^B, and wire 28 to rail 1, and from rail 1^a, through wire 29, impedance 13, and wire 30 back to winding 8 of transformer J^B. When relay K^B is de-energized, however, current of the opposite relative polarity, which I will term "reverse relative polarity", is supplied to the rails of section A—B from 75 secondary 9 of transformer J^B, over a circuit which passes from one terminal of winding 9, through wire 31, back contact 27 of relay K^A and wire 28 to rail 1 and from rail 1^a, through wire 29, impedance 13 and wire 31 80 back to winding 9 of transformer J^B. The circuits for each of the remaining transformers J are similar to those just traced for transformer J^B, and it follows therefore that the rails of each section, and hence primary 85 4 of the associated transformer T are supplied with alternating current of one relative polarity or the other according as the relay K for the section next in advance is energized or de-energized.

95 The current in the secondary of each transformer T is best rectified when the electro-motive force of the secondary is in phase with, or 180° out of phase with, the displacement of reed 11 of the associated rectifier D. It will be assumed that when current of normal relative polarity is being supplied to the rails of section A—B, the electromotive force of the secondary of transformer T^A is in 100 phase with the displacement of reed 11 of rectifier D^A. Assuming that under these conditions

ditions the reed 11 of the rectifier is swung to the right into engagement with contact 11-11^c when the upper terminal of secondary 5 is positive with respect to the common terminal *d*, current of what will be termed "normal" polarity will flow through relay K^A from secondary 5 of transformer T^A as long as contact 11-11^c is closed. When contact 11-11^b is closed, during the next half cycle of the current supplied to winding 12, the common terminal *d* will be negative with respect to the lower terminal of secondary 6 so that current will flow in the same direction as before through relay K^A from secondary 6 of transformer T^A as long as contact 11-11^b is closed. It follows that when current of normal relative polarity is being supplied to the rails of section A-B, relay K^A is continuously supplied with rectified current which flows at all times in the same direction through this relay. Under these conditions the front contacts of the relay are closed and armature 17 is swung to the left to close its normal contact.

When the rails of section A-B are supplied with current of reverse relative polarity, however, the electromotive force of the secondary of transformer T^A will be 180° out of phase with the displacement of reed 11 of rectifier D^A. It follows that terminal *d* will be positive with respect to the upper terminal of secondary 5 when contact 11-11^c is closed and terminal *d* will be positive with respect to the lower terminal of secondary 6 when contact 11-11^b is closed. Under these conditions, then, current will at all times flow through relay K^A in the same direction but the direction of this current will be opposite from the direction of the current which flows through the relay when winding 4 of transformer T^A is supplied with normal relative polarity. The polarity of the current supplied to relay K^A when primary 4 is supplied with current of reverse polarity will be called "reverse" polarity, and when the relay is supplied with such current its front contacts will be closed and armature 17 will be swung to the right to close its reverse contact. The operation of the remaining relays K is similar to that of relay K^A and will be understood without further explanation.

Each section is provided with a trackway signal designated by the reference character S with a suitable exponent and each comprising, as here shown, three electric lamps G, Y and R. When relay K^A is energized by current of normal polarity, current flows from secondary 10 of transformer J^A, through wire 14, front contact 15 of relay K^A, wire 16, normal contact 17 of relay K^A, wire 18, lamp G^A and wires 19, 20 and 21 back to secondary 10 of transformer J^A, thereby lighting lamp G^A to display a proceed indication. When relay K^A is ener-

gized by current of reverse relative polarity, current flows from secondary 10 of transformer J^A, through wire 14, front contact 15 of relay K^A, wire 16, reverse contact 17 of relay K^A, wire 22, lamp Y^A, and wires 23, 20 and 21, back to secondary 10 of transformer J^A. When this circuit is closed lamp Y^A is lighted to give a caution indication. When relay K^A is de-energized, as by the presence of a train in section A-B, back contact 15 of relay K^A is closed and current flows from secondary 10 of transformer J^A, through wire 14, back contact 15 of relay K^A, wire 24, lamp R^A, and wires 25 and 21 back to secondary 10 of transformer J^A. When this circuit is closed lamp R^A is lighted to give a stop indication. Each of the remaining lamps G, Y and R is controlled by the associated relay K in a manner similar to that just described in connection with lamps G^A, Y^A and R^A.

As shown in the drawing, sections A-B and B-C are unoccupied, and a train, indicated diagrammatically at V, occupies the section to the right of point C. Current is therefore shunted away from primary 4 of transformer T^C and no current is supplied to relay K^C although rectifier D^C operates continuously. Relay K^C is therefore de-energized and lamp R^C is lighted to give a stop indication. Back contact 27 of relay K^C being closed, current of reverse relative polarity is supplied to the rails of section B-C from secondary 9 of transformer J^C. This current is supplied to primary 4 of transformer T^B, and since rectifier D^B is operated continuously, the relay K^B is supplied with current of reverse polarity so that this relay is energized in the reverse direction. Lamp Y^B is therefore lighted to indicate caution, and current of normal relative polarity is supplied to the rails of section A-B from secondary 8 of transformer J^B over front contact 27 of relay K^B. Current of normal relative polarity is therefore supplied to primary 4 of transformer T^A and current of normal relative polarity energizes relay K^A. Lamp G^A is therefore lighted to indicate proceed, and current of normal relative polarity is supplied to the rails of the section to the left of point A.

Referring now to Fig. 2, in the train control system here illustrated, each track section is provided with a track relay designated by the reference character H with an exponent corresponding to the location and comprising a movable contact 32 arranged to occupy a left-hand or normal position, a right-hand or reverse position, or an intermediate position, according as the relay is supplied with current of normal relative polarity, reverse relative polarity or is de-energized. Each track relay H is connected across the rails adjacent the entrance end of the associated section. Each track sec-

tion is supplied with alternating track circuit current from a track transformer designated by the reference character P with an exponent corresponding to the location and 5 having a secondary 34 constantly connected across the rails adjacent the exit end of the corresponding section through the impedance 13. The supply of alternating current to primary 33 of each track transformer 10 P is controlled by the adjacent track relay so that when that relay is energized in either direction current of normal relative polarity is supplied to primary 33 from winding 9 of the adjacent transformer J, 15 but that when the track relay is de-energized, current of reverse relative polarity is supplied to the primary 33 from secondary 8 of the associated transformer J. It follows that the rails of each section are supplied 20 with track circuit current of normal relative polarity or reverse relative polarity according as the track relay for the section next in advance is energized or de-energized.

Means are also provided for supplying the 25 rails of each section with "loop" current which flows through the rails of the section in parallel. For this purpose each section is provided with a resistor 37 connected across the rails adjacent the entrance end 30 of the section and a second resistor 38 connected across the rails adjacent the exit end of the section. The loop current is supplied to the rails of the section at the mid-points of these resistors 37 and 38. The immediate 35 source of loop current for each track section is a loop transformer designated by the reference character L with an appropriate exponent and located adjacent the exit end of the corresponding section. Primary 40 36 of each loop transformer L is constantly supplied with alternating current from line wires 3 and 3^a and the secondary 35 of each loop transformer L is constantly connected to the mid-point of resistor 37 of the 45 associated section through an auxiliary conductor which extends throughout the section parallel to the rails and is designated in the drawing by the reference character X. It follows that loop current is constantly 50 supplied to the rails of each section.

The loop current and track circuit current supplied to the rails of the sections control governing means located on a train V^a occupying the section to the left of a point 55 A. This train is provided with two receivers E and F each comprising two magnetizable cores 43 and 43^a carried on the train in inductive relation with the two track rails 1 and 1^a respectively. Core 43 is provided 60 with a winding 44, and core 43^a is provided with a similar winding 44^a. The receiver F is located in advance of the forward axle 42 of the train and the windings 44 and 44^a of this receiver are connected in series 65 in such manner that the voltages induced

therein by track circuit current flowing in opposite directions in the two track rails at an instant are additive. Receiver F is connected through a suitable amplifier 48 with an auto transformer T. The receiver 70 E is located in rear of the forward axle of the train, usually between the locomotive and the tender, and the windings 44 and 44^a of this receiver are connected in series in such manner that the voltages induced therein by loop current flowing in the same direction in the two track rails at an instant are additive. The receiver E is connected 75 through a suitable amplifier 45 to the operating winding 12 of a vibrating rectifier 80 D. The relay K is provided with two circuits, one including winding 5 of transformer T and contact 11-11^b of rectifier D, and the other including winding 6 of transformer T and contact 11-11^c of rectifier D. The relay K is supplied with rectified current of one polarity or the other in accordance with the relative polarities of the currents supplied to winding 12 and transformer T in a manner similar to the 85 control of relay K in Fig. 1. The parts are so arranged that when the train occupies a stretch of track which is being supplied with loop current and with track circuit current of normal relative polarity, relay K is supplied with rectified current of normal polarity 90 so that the relay is energized in the normal direction; contact 17 is then swung to the left and front contact 51 is closed. Current therefore flows from a suitable 95 source of energy such as a battery 50 through lamp G to display a proceed indication. When the train occupies a stretch of track which is being supplied with track circuit current of reverse relative polarity and also with loop current, relay K is supplied with rectified current of reverse polarity thereby 100 closing front contact 51, swinging contact 17 to the right, and closing the circuit for lamp Y. This lamp therefore becomes lighted to 105 indicate caution. If the supply of loop current to the train is for any reason interrupted the rectifier D ceases to operate and the reed 11 then occupies its intermediate 110 position in which it is illustrated in the drawing and relay K is de-energized. If the supply of track circuit current to the train is interrupted, no current is supplied to relay K and this relay becomes de-energized. In case either loop current or track 115 circuit current is interrupted, therefore, the de-energization of relay K closes the circuit for lamp R at back contact 51, and a stop indication is received on the train.

As shown in the drawing the section to the right of point C is occupied by a train V. Relay H^c is therefore de-energized and current of reverse relative polarity is supplied to the rails of section B-C. Loop current 120 is constantly supplied to this section by 125 130

transformer L^c . Relay H^B is energized in the reverse direction and track circuit current of normal relative polarity is supplied to the rails of section A—B by transformer P^B . Loop current is supplied to the rails of this section by transformer L^B . In similar manner relay H^A is energized in the normal direction and loop current and track circuit current of normal relative polarity are supplied to the rails of the section to the left of point A by transformers L^A and P^A , respectively.

It will now be assumed that the train V^a proceeds through the stretch of track shown in the drawing. As this train proceeds through section A—B, the phase relation of the loop current and the track circuit current supplied through receivers E and F to the rectifier D and transformer T is such that relay K is energized in the normal direction and lamp G is lighted to indicate proceed. When the train enters section B—C however, the reversal of the polarity of the track circuit current causes relay K to be supplied with current of reverse polarity so that lamp Y is lighted to indicate caution. When the train enters the section to the right of point C the interruption of track circuit current due to the shunting effect of the wheels and axles of train V^a occupying this section interrupts the supply of current to transformer T on the train V^a so that relay K becomes de-energized and lamp R is lighted to give a stop indication.

In the absence of some preventative means the reactance of the track rails and the leakage of the current from the track rails through the ground might result in displacement of the phase relations between the loop current and the track circuit current at different points in any given section. Since the operation of the relay K depends upon the phase relation of these currents in the portion of track which is occupied by the train, such variation in phase relation would be undesirable, and to prevent its occurrence a number of reactors 39 are introduced in the auxiliary conductor X at spaced points throughout the section. A plurality of non-inductive leakage paths represented in the drawing by resistances 40 are provided between this conductor and the ground, one of these resistances 40 being connected between the conductor and the ground 41 between each two adjacent reactors 39. The decedent has discovered that with this arrangement the phase relation between the loop current and the track circuit current is substantially constant at all points in the section. It should be noted that with this arrangement the loop current in the rails is of considerably greater magnitude adjacent the ends of the section than at the middle of the section because a portion of the loop current flows from the rails to the auxiliary conductor through the

leakage paths including the resistances 40, thereby depriving the rails adjacent the center of the section of a portion of the loop current. This feature is not dangerous however because the loop current operates the rectifier D and the only effect of increased current is to increase the power available at the entrance end of a section to pick up the relay K, and the diminishing loop current which is supplied to the train at intermediate points in the section is sufficient to hold this relay in its energized condition after the relay has once been energized.

Attention should also be directed to the fact that the control of the polarity of the track circuit current by track relay H in Fig. 2 could be accomplished by the relay K connected as shown in Fig. 1. Either the relays K in Fig. 1 or the track relays H in Fig. 2 can be utilized to operate governing means, not shown in the drawing, in any desired manner.

One advantage of the traffic controlling apparatus embodying relays controlled in accordance with the operation of relay K is that successful operation can be accomplished by extremely small values of current in the track rails.

Another advantage is that since the rectifier D is mechanically tuned to a given frequency the system is substantially immune to the effects of alternating currents of a frequency other than that at which the apparatus is intended to operate.

As illustrated in the drawings the supply of alternating current to the rails for the control of relay K is uninterrupted, but the apparatus could be used equally well in conjunction with track circuit currents or loop currents either or both of which are periodically interrupted.

Although only two forms of railway traffic controlling apparatus embodying the invention are herein shown and described, it is understood that various changes and modifications may be made therein within the scope of the appended claims without departing from the spirit and scope of the invention.

Having thus described the invention what is claimed is:

1. In combination, a section of railway track, means for supplying the rails of said section with alternating current of one relative polarity or the other, a relay responsive to the polarity of the current supplied thereto, a rectifier, and means including the rectifier for supplying the relay with current of one polarity or the other depending upon the relative polarity of the alternating current flowing in the track rails.
2. In combination, a section of railway track, means for supplying the rails of said section with alternating current of one relative polarity or the other, a relay receiving

energy from the track rails and responsive to the polarity of the current supplied thereto, and a rectifier interposed between said relay and the rails for controlling the polarity of the current supplied to the relay in accordance with the relative polarity of the current supplied to the rails.

3. In combination, a source of alternating current, a relay responsive to the polarity of the direct current supplied thereto, and a vibrating relay supplied with alternating current for supplying the relay with rectified current of one polarity or the other depending upon the phase relation of the current supplied to the rectifier with respect to the current from said source.

4. Railway traffic controlling apparatus comprising a transformer, a vibrating rectifier, means for separately supplying said transformer and rectifier with alternating currents, the phase relation of which depends upon traffic conditions, a polarized direct current relay, means including said rectifier for supplying rectified current of one polarity or the other to said relay from said transformer depending upon the phase relation of such currents, and governing means controlled by said relay in accordance with the polarity of the current supplied to the relay.

5. Railway traffic controlling apparatus comprising a stretch of railway track, a transformer, a vibrating rectifier, means for separately supplying said transformer and said rectifier with alternating currents the phase relation of which depends upon traffic conditions in said stretch, a polarized direct current relay supplied with rectified current of one polarity or the other from said transformer by said rectifier in accordance with the phase relation of such alternating currents, and governing means controlled by said relay in accordance with the polarity of the current supplied to the relay.

6. Railway traffic controlling apparatus comprising a stretch of railway track, a transformer, a vibrating rectifier, means for separately supplying said transformer and said rectifier with alternating currents, means responsive to traffic conditions for controlling the phase of the current supplied to said transformer, a polarized direct current relay supplied with rectified current of one polarity or the other from said transformer by said rectifier in accordance with the phase relation of such alternating currents, and governing means controlled by said relay in accordance with the polarity of the current supplied to the relay.

7. In combination, a stretch of railway track, a vibrating rectifier constantly supplied with a first alternating current, means for supplying a second alternating current to the rails of the stretch, a transformer receiving energy from the rails of the stretch,

means responsive to traffic conditions for controlling the phase relation of said two alternating currents, a polarized direct current relay, means including said rectifier for supplying said relay with rectified current of one polarity or the other depending upon the phase relation of said two alternating currents, and governing means controlled by said relay.

8. In combination, a stretch of railway track, a vibrating rectifier constantly supplied with a first alternating current, means for supplying a second alternating current to the rails of the stretch, a transformer connected with the rails of the stretch, means responsive to traffic conditions for controlling the phase relation of such alternating currents, a polarized direct current relay, means including said rectifier for supplying said relay with rectified current of one polarity or the other depending upon the phase relation of said two alternating currents, and a trackway signal controlled by said relay.

9. In combination, a plurality of successive sections of railway track, a vibrating rectifier for each section constantly supplied with alternating current, a transformer for each section having its primary connected with the rails of the associated section, a polarized direct current relay for each section, means for each section including the associated rectifier for supplying rectified current of one polarity or the other to the corresponding relay from the secondary of the adjacent transformer depending upon the relative polarity of the current supplied to such transformer, means controlled by each track relay for supplying the rails of the section next in rear with alternating current of one relative polarity or the other according as the relay is energized or de-energized, and governing means for each section controlled by the corresponding relay in accordance with the polarity of the current supplied to such relay.

10. Railway traffic controlling apparatus comprising a train carried rectifier, a train carried transformer, means located partly in the trackway for supplying said rectifier and the primary of said transformer with alternating currents the phase relation of which depends upon traffic conditions, a polarized direct current relay, and means including said rectifier for supplying the relay with current of one polarity or the other from the secondary of said transformer depending upon the phase relation of said alternating currents.

11. Railway traffic controlling apparatus comprising a stretch of track, a source of alternating loop current; a circuit including said source, the rails of the stretch in parallel, and an auxiliary conductor extending the length of the stretch; a plurality of reactors

inserted at spaced intervals in said auxiliary conductor, a plurality of leakage paths between said conductor and the ground, one such leakage path being located between each 5 two adjacent reactors, means for supplying alternating track circuit current to the rails of the stretch in series, and means located on a train and responsive to the phase relation of the track circuit current and the loop 10 current in the rails under such train.

12. In combination, a polarized direct current relay, a transformer winding, means for connecting the mid-point of said transformer winding with one terminal of said 15 relay, a rectifier having an operating winding and a vibratable reed, two contacts con-

trolled by said reed and arranged to be operated alternately when said operating winding is energized, means controlled by said contacts for connecting the two terminals 20 respectively of said transformer winding with the remaining terminal of said relay, and means for separately supplying the operating winding of said rectifier and said transformer winding with alternating currents of different phase relations whereby current of one polarity or the other is supplied to the relay depending upon the phase relation of such alternating currents.

In testimony whereof I affix my signature.
HALVOR HOLTE,
Administrator of Harold O. Holte, deceased.
